CLAIM

The ornamental design for an attachable artist's easel, as shown and described.

DESCRIPTION

FIG. 1 is a perspective top view of an attachable artist's easel showing my new design;

FIG. 2 is a front view thereof;

FIG. 3 is a right side view thereof;

FIG. 4 is a top side view thereof;

FIG. 5 is a bottom side view thereof; and,

FIG. 6 is a rear view thereof.

The broken lines shown are included for the purpose of illustrating portions of the attachable artist's easel that form no part of the claimed design.

1 Claim, 5 Drawing Sheets(56)
